CLAIM

(57) The ornamental design for a foldable holding device with light for tablet computer, as shown and described.

DESCRIPTION

FIG. 1 is a front view of a foldable holding device with light for tablet computer;

FIG. 2 is a back view thereof;

FIG. 3 is a top view thereof;

FIG. 4 is a bottom view thereof;

FIG. 5 is a left view thereof;

FIG. 6 is a right view thereof;

FIG. 7 is a perspective view thereof, showing the foldable holding device in a folded state; and,

FIG. 8 is a perspective view thereof, showing the foldable holding device in an unfolded and working state.
